UNITED STATES PATENT OFFICE.

EBEN RAY PACKER, OF NEW ROCHELLE, NEW YORK, ASSIGNOR TO Q & C COMPANY,
OF NEW YORK, N. Y., A CORPORATION OF MAINE.

SWITCH-POINT PROTECTOR.

Application filed September 22, 1926. Serial No. 136,940.

This invention relates to improvements in switch point protectors for railway switches or turnouts and consists in features of construction and arrangement designed to produce an improved device adapted to be efficient in eliminating or reducing wear and damage to switch points, to reduce derailments at switch points and the hazards and costs in connection therewith, to have adequate strength, to be economical of manufacture, to allow of economy in the replacement or renewal of the wearing surfaces or parts and to produce other important advantages over devices as heretofore used for the purpose.

The device of the present invention may desirably be designed whereby in operating to relieve the switch point of excessive wear and damage, it is positioned to be engaged by the outer or tread side surface of a car or locomotive wheel and is of a form whereby such engagement will move the wheel laterally and in the direction of switching a distance sufficient to be fully clear of endwise engagement with the switch point and to relieve the reduced end portion of the switch point of excessive pressures. This desirable arrangement provides for the positioning of the protector member at the outer side of the rail adjacent to the switch point, which is important from the operating standpoint in that it fully eliminates any hazard or danger factor as related to the protector member becoming displaced or loosened as would be present where the protector member positioned at the inner side of the track rail or within the flangeway.

A particular feature of the present improvements resides in a perfected form and design of the protector member which is preferably composed of two parts comprising a supporting member and an insert or bearing portion member formatively providing the wearing or contact surfaces and which latter member may desirably be made of a manganese steel casting so as to afford greater durability and resistance to wear. Further desirable features include the relative design of the supporting member and the wear insert member whereby the insert member will be positively secured in its supporting and operating position in the assembling of the device and whereby the severe lateral thrusts, as well as the longitudinal pressures, will be resisted by the supporting

member independent of separable securing means.

The foregoing and other features and advantages of my improved device will be understood by reference to the accompanying drawing wherein like reference numerals are applied to the corresponding parts in the several views.

In the drawings:

Fig. 1 is a plan view of a protector member of my invention as installed in connection with a switch structure.

Fig. 2 is a perspective view of a protector member embodying the features of my present invention.

Fig. 3 is a vertical cross-sectional view taken on line $x-x$ of Fig. 5.

Fig. 4 is a vertical cross-sectional view taken on line $y-y$ of Fig. 5.

Fig. 5 is an isometric view of my improved protector as viewed from the inside of the track rail.

Fig. 6 is a vertical cross-sectional view similar to Fig. 4, showing a suitable modification of the structure.

The improved switch point protector as shown in Figs. 1 to 5, comprises a deflector member a adapted to be positioned as shown upon the outer side of the main track rail 1, opposite to the extreme end or reduced portion of the movable rail or switch point 2. The protector a consists of a supporting member 2 composed of an upper or head portion 3, a vertical web portion 4 and a base or flange portion 5. Upon the upper or head portion 3, there is removably mounted a separable insert or bearing member 6 having an upwardly extended longitudinal bearing portion or deflecting flange 7, positioned to have its inwardly directed surface engaged by the outer or non-flange surface of a car wheel for the purpose of inwardly deflecting the latter and for this purpose, having its end portions outwardly flared as shown at 8-8. The separable insert member 6 may desirably be made of a manganese steel casting or of a high grade steel alloy having the properties of high resistance to wear and is further of a form with relation to the supporting member whereby the severe outward pressures applied thereto will be resisted by and transmitted to the supporting member independent of bolts or other securing means. To this end, the head portion of the supporting member 2 is of a form pro-

viding inner and outer vertical and longitudinally extending shoulder portions 9 and 10 and the underside of the insert member 6 is of a complementary form to provide shoulders opposed to and engaging the shoulders 9 and 10, thereby resisting outward movement of the insert member with reference to the supporting member 2. The head enlargement of the supporting member is desirably formed at its inner marginal edge with spaced upwardly extended lugs 11 having engagement with the underside of the rail head.

In further accordance with the present invention, the insert bearing member is formed at its inner edge portion with a shoulder 12 bearing against the side of the track rail head and with lower inner marginal shoulder extensions or lugs 13, formed to have bearing engagement with the under side or fishing surface of the track rail head with the function of resisting tilting action under the severe lateral thrust received from the rolling stock. A further desirable feature of my improved construction consists in provision for inter-engagement between the insert bearing member 6 and the supporting member 2 for the purpose of securing the insert member against longitudinal movement with reference to the supporting member. To this end the inner marginal flange portion of the head 3 of the supporting member is cut out or recessed at 15—15 and the insert member is formed at its lower, inner marginal portion with downwardly extended lugs or shoulders 16, formed as enlargements of the flange 13 and spaced to fit the recesses 15 to provide shoulder engagement between the insert and supporting members opposing longitudinal movement of the former.

The base portion is formed, as shown, to have spacing engagement with the fishing surface of the rail base flange and is provided with outwardly extending base flange portions 17 adapted for spiking to the ties and is formed at its underside with a longitudinal recess 18 to receive a shoulder enlargement 19 upon the bearing plate or switch plate 19, positioned to underlie the rail in the usual manner. The deflector member as a whole is arranged to be secured to the track rail by means of bolts 20, fitted to suitable apertures in the rail and deflector member and threaded at their outer end portions to receive the clamping nuts 21. As a further desirable feature of improvement the separable insert member 6 is formed with depending lugs 22 having openings to receive the securing bolts, whereby the bolts operate as a securing means for the device as a whole and likewise function to secure the insert member against displacement.

While I have described and shown an ap-

proved embodiment of the features of my present improvements, it will be understood that varied modifications may be made therein without departing from the scope of the invention as defined in the appended claims. 70 As illustrative thereof, there is shown in Fig. 6 a desirable modified structure wherein the device conforms generally to the arrangement of the preceding figures but wherein the head portion of the supporting member and the insert member 6' are apertured to receive the clamping bolts 24 fitted with the nuts 26 for independently securing the insert member. As will be noted, this arrangement allows of removing the insert member for replacement without dependence upon the main securing bolts for attachment.

Having described my invention, I claim:

1. A switch point protector adapted for use in combination with a main rail and a movable switch point operatively associated therewith and to be positioned for deflecting the car wheel in the direction of switching so as to clear the end of the switch point, comprising a supporting member and a separable bearing insert member formed with a deflecting shoulder portion positioned to be engaged by the car wheel and said supporting and insert members being formed to have inter-engagement opposed to relative movement of said members both in lateral and longitudinal direction.

2. A switch point protector adapted for use in combination with a main rail and a movable switch point operatively associated therewith and to be positioned for deflecting the car wheel in the direction of switching so as to clear the end of the switch point, comprising a supporting member and a separable bearing insert member formed with a deflecting shoulder portion positioned to be engaged by a car wheel, said insert member having an inwardly extended shoulder engaging the under side of the rail head and said supporting and insert members being formed for inter-engagement opposed to relative movement both in lateral and longitudinal direction.

3. A switch point protector adapted for use in combination with a main rail and a movable switch point operatively associated therewith and to be positioned for deflecting the car wheel in the direction of switching so as to clear the end of the switch point, comprising a supporting member and a separable bearing insert member formed with a deflecting shoulder portion positioned to be engaged by a car wheel, said supporting member and insert member being formed with aligned openings and securing bolts fitted to said openings and to the main rail for securing said members in assembled relation and in operating position.

4. A switch point protector of the character described, comprising a supporting mem-

ber and a separable bearing insert member formed with a deflecting shoulder portion positioned to be engaged by a car wheel, said supporting member being composed of a 5 head portion, a web portion and a base portion, said head portion being formed with a shoulder directed toward the rail and said insert member being formed with an outwardly directed shoulder opposed to said 10 supporting member shoulder and with depending lugs for engagement with the supporting member to oppose relative longitudinal movement of the members.

5. A switch point protector of the character described comprising a supporting member and a separable bearing insert member formed with a deflecting shoulder portion positioned to be engaged by a car wheel, said supporting member being composed of a 15 head portion, a web portion and a base portion, said head portion being formed to have engagement with the fishing surface of the rail head and with a shoulder directed toward the rail and said insert member being 20 formed with an outwardly directed shoulder opposed to the supporting member shoulder and with an inwardly extended shoulder engaging the fishing surface of the rail head and means for securing the protector with 25 relation to the rail.

6. A switch point protector of the character described comprising a supporting member and a separable bearing insert member formed with a deflecting shoulder portion 30 positioned to be engaged by a car wheel, said supporting member being composed of a head portion, a web portion and a base portion, said head portion being formed with spaced inwardly extended lug portions 35 engaging the underside of the rail head and with a longitudinally extending shoulder directed toward the rail and said insert member being formed with an outwardly directed shoulder opposed to the supporting member 40 shoulder and with inwardly extended lug portions positioned to engage the underside of the rail head and longitudinally opposed to the supporting member lugs and means for securing the protector with 45 relation to the rail.

7. A switch point protector of the character described comprising a supporting member and a separable bearing insert member formed with a deflecting flange portion positioned to be engaged by a car wheel, said 55 supporting member being composed of a head portion, a web portion and a base portion, said head portion being formed with spaced inwardly extending lugs engaging the underside of the rail head and with a longitudinally extending shoulder directed toward the rail and said insert member being 60 formed with an outwardly directed shoulder opposed to the supporting member shoulder and with inwardly extended lug portions 65 positioned to engage the underside of the rail head and longitudinally opposed to the supporting member lugs and with depending portions having openings for a securing means and securing bolts fitted to apertures 70 in the rail and supporting member and to said depending portion openings for securing the protector to the rail and the parts in assembled relation.

8. A switch point protector of the character described comprising a supporting member and a separable bearing insert member formed with a deflecting flange portion positioned to be engaged by a car wheel, said supporting member being composed of a 75 head portion, a web portion and a base portion, said head portion being formed to have engagement with the underside of the rail head and with a shoulder directed toward the rail, said base portion formed to bear 80 upon the upper surface of the rail base flange and formed upon its underside with a longitudinally extending groove, said insert member being formed with an outwardly directed shoulder opposed to the supporting member 85 head shoulder and with shoulders engaging the supporting member in opposition to longitudinal movement and a tie plate positioned to underlie the track rail and having a shoulder fitted to the groove of the supporting member base portion.

Signed at New York city in the county of New York and State of New York this 21st day of July, A. D. 1926.

EBEN RAY PACKER.
